LINK CHAIN FOR A BRACELET OR THE LIKE

Emil Rodriguez, New York, N.Y., assignor to Jacoby-Bender, Inc., Woodside, N.Y., a corporation of New York

Filed Dec. 10, 1962, Ser. No. 72,798

Term of patent 7 years

(Cl. D45—4)

FIG. 1

FIG. 2

FIG. 3

FIG. 4

FIG. 5

FIG. 1 is a top plan view of a link chain for a bracelet, showing my new design;

FIG. 2 is a top plan view, on an enlarged scale, of the top shell of one of the links of the chain of FIG. 1;

FIG. 3 is a side elevational view of the top shell of FIG. 2, taken from the left hand side of FIG. 2;

FIG. 4 is an end elevational view, on a further enlarged scale, of the top shell of FIG. 2; and

FIG. 5 is a cross sectional view on a further enlarged scale of the top shell of FIG. 2 taken along the line 5—5 of FIG. 2.

I claim:

The ornamental design for a link chain for a bracelet or the like, as shown.
